DESIGN.

J. W. ROGERS, dec'd., J. W. ROGERS, Adm'r.
Coffin-Lid Lifter.

No 11,798.

Patented June 1, 1880.

UNITED STATES PATENT OFFICE.

JULIUS W. ROGERS, (ADMINISTRATOR OF THE ESTATE OF J. WILBUR ROGERS, DECEASED,) OF WEST MERIDEN, CONNECTICUT, ASSIGNOR TO C. ROGERS & BROTHERS, OF SAME PLACE.

DESIGN FOR COFFIN-LID LIFTERS.

SPECIFICATION forming part of Design No. 11,798, dated June 1, 1880.

Application filed May 3, 1880. Term of patent 7 years.

To all whom it may concern:

Be it known that J. WILBUR ROGERS, deceased, late of West Meriden, in the county of New Haven and State of Connecticut, did invent a new Design for Coffin-Lid Lifters; and I do hereby declare the following, when taken in connection with the accompanying drawing, and the letters of reference marked thereon, to be a full, clear, and exact description of the same, and which said drawing constitutes part of this specification, and represents a perspective view.

This invention relates to a design for a handle to be attached to coffin-lids for convenience in lifting them; and the design consists in the representation of a calla-lily lying on a bed of calla-leaves, the stem of the lily coiled to form the handle, as shown in the accompanying illustration.

The bed or base consists of the representation of three calla-leaves placed longitudinally, and on these rests the lily near its stem end, the stem bent and curled upward to form the lifting-handle A, as shown in the accompanying illustration.

I claim—

The design for coffin-lid lifters, consisting of the representation of a bed of calla-leaves, with a calla-lily resting thereon, its stem coiled to form the handle A, as shown in the accompanying illustration.

JULIUS W. ROGERS,
*Administrator of the estate of J. Wilbur Rogers,
inventor.*
